(57) **CLAIM**

The ornamental design for a pipe painter handle, as shown and described.

DESCRIPTION

FIG. 1 is a front top perspective view of a pipe painter handle showing my new design as seen from the left side thereof.

FIG. 2 is a front bottom perspective view thereof.

FIG. 3 is a rear bottom perspective view thereof.

FIG. 4 is a top plan view thereof.

FIG. 5 is a bottom plan view thereof.

FIG. 6 is a left side view thereof, the right side being a mirror image.

FIG. 7 is a front end view thereof; and,

FIG. 8 is a rear end view thereof.

The areas bounded by broken lines represent internal boundaries of the claimed design and form no part thereof.

1 Claim, 3 Drawing Sheets

FIG. 3

FIG. 4
